ROTARY TOOTH BRUSH

George F. W. King, Helena, Mont.

Application January 26, 1937, Serial No. 122,435

1 Claim. (Cl. 74—89)

This invention relates to rotary tooth brushes and has for the primary object the provision of a simple and inexpensive device of this character which will permit thorough cleaning of teeth and the spaces therebetween and which may be easily operated by comparatively short thumb and finger movements and may be successfully used by either hand of a person.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating a tooth brush constructed in accordance with my invention.

Figure 2 is a sectional view taken on the line 2—2 of Figure 1.

Figure 3 is a transverse sectional view taken on the line 3—3 of Figure 2.

Referring in detail to the drawing, the numeral 1 indicates a sleeve slidably received within a cylinder 2, one end of which is closed by a movable cap 3 having formed integrally therewith a ring or eye 4 through which may be positioned a person's thumb. The other end of the cylinder 2 or the end which slidably receives the sleeve 1 has an internal shoulder 6 to be abutted by a flange 7 formed on one end of the sleeve for limiting the movement of the sleeve outwardly of the cylinder.

Rotatably supported and extending through the sleeve 1 is a shaft 8, a portion of which has a bore 9 to receive a coil spring 10. Slidably received within the bore 10 and also within the spring is a guide rod 11 having fitting engagement with a bearing 12 formed on the inner face of the cap 3. The purpose of the guide rod 11 is to prevent the spring bending out of shape or kinks forming therein during the use of the device.

A feed nut 13 is keyed or otherwise secured to the shaft 8 and meshes with feed threads 14 formed in the cylinder 2. Secured to the shaft 8 in any suitable manner is a shank 15 carrying a series of tufts of bristles 16. A collar 17 is

threaded to the sleeve 1 and has formed thereon finger rests 18. A shoulder 19 is formed on the sleeve to cooperate with a thrust collar 20 formed on the shaft.

The bristles during non-use of the device are protected by a casing 21 and the latter has locking grooves 22 to receive lugs 23 formed on the collar 17 thereby removably securing the casing to the sleeve with the bristles confined therein.

In use, the casing 21 is removed and the operator places two fingers against the finger rests 18 and the thumb in the ring 4 and by moving the thumb towards the fingers the cylinder 2 will be slid on the sleeve 1. The relative sliding movement between the cylinder 2 and the sleeve 1 brings about rotation of the shaft 8 due to the feed nut meshing with the feed threads of the cylinder, consequently the bristles are rotated and when placed against the teeth and moved upwardly and downwardly with the rotary motion will thoroughly remove foreign matter from the teeth and from the spaces between the teeth.

The thumb and finger motion above described causes rotation of the brush in one direction compressing the spring 10, and the brush is rotated in the reverse direction by the expansion of the spring when the thumb pressure is released on the ring 4.

Having described the invention, I claim:

A rotary toothbrush comprising a sleeve, a shaft journaled in said sleeve and fashioned with a hollow section and adapted to have a work implement secured thereto, a cylinder slidably mounted on said sleeve and provided with feed threads formed in the bore thereof, a feed nut fixed to said shaft and meshing with said threads, a coil spring extending into said hollow section of said shaft and bearing against one end of said cylinder for rotating said implement upon expansion of said spring from compressed condition in said section, said sleeve and cylinder manually actuatable towards each other for rotating said implement in the opposite direction and compressing said spring, and a guide rod carried by said cylinder and extending through said spring into said section to maintain said spring in aligned relation with said section.

GEORGE F. W. KING.
